Primary Examiner — Shannon W Morgan*Assistant Examiner* — Daniel J Vogt*(74) Attorney, Agent, or Firm* — Westbridge IP LLC(57) **CLAIM**

The ornamental design for an LED display cabinet, as shown and described.

DESCRIPTION

FIG. 1 is a front, right and bottom perspective view of an LED display cabinet showing our new design;

FIG. 2 is a rear, left and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view taken from circle 9 in FIG. 1;

FIG. 10 is a partial enlarged view taken from circle 10 in FIG. 1;

FIG. 11 is a partial enlarged view taken from circle 11 in FIG. 1; and,

FIG. 12 is a partial enlarged view taken from circle 12 in FIG. 2.

The dash-dash broken lines in the drawings depict the portions of the LED display cabinet that form no part of the claimed design.

The dot-dash broken lines in the drawings depict the boundaries of the partial enlarged views that form no part of the claimed design.

1 Claim, 12 Drawing Sheets(56)
